PUMP AND BLOWER CLUTCH FOR
WASHER-DRYERLeo H. Sauer, St. Joseph, Mich., assignor to Whirlpool
Corporation, St. Joseph, Mich., a corporation of
DelawareFiled Aug. 30, 1963, Ser. No. 305,724
11 Claims. (Cl. 68—12)

This invention relates generally to laundry apparatus and more particularly relates to a pump and blower clutch and drive system for a combination washer-dryer wherein the blower and the pump may be selectively inactivated during the washing and drying periods, respectively, thereby preventing the blower housing from becoming wet and preventing lint build up during the washing operation and eliminating the pump during drying operations to reduce power requirements on the driving motor.

It is an object of the present invention to provide an improved drive system for a combination washer-dryer wherein the pumping means for the liquid circuitry of the machine and the blower for the air circuitry of the machine may be selectively activated and inactivated.

It is a further object of the present invention to provide a washer-dryer wherein the blower may be inactivated during the washing cycle to prevent the blower housing from becoming wet and to prevent lint build up in the blower housing.

A still further object of the present invention is to provide a combination washer-dryer wherein the liquid pumping means may be inactivated during the drying cycle to reduce power requirements on the drive motor.

Yet another object of the present invention is to provide a pump and blower system for a washer-dryer utilizing a common driving motor and incorporating a clutch-type drive system.

A still further object of the present invention is to provide a pump and blower clutch and drive system for a washer-dryer of the type automatically operated by a sequential control means through a programmed series of washing and drying steps and wherein the pump and blower means of the apparatus may be placed under direct control of the sequential control means for selective activation and inactivation at times corresponding to prescribed washing and drying operations.

It is a further object of this invention to provide a pump and blower drive system that maybe selectively inactivated during the washing and drying periods, thereby reducing the wear on the components of the blower and pump.

Many other objects, features and additional advantages of the present invention will become manifest to those versed in the art upon making reference to the detailed description which follows and the accompanying sheets of drawings in which a preferred embodiment of a washer-dryer incorporating the principles of the present invention is shown by way of illustrative example.

On the drawings:

FIGURE 1 is a rear view showing the back of a combination washer-dryer;

FIGURE 2 is an enlarged view similar to FIGURE 1 but showing additional details of the driving system provided in accordance with the principles of the present invention;

FIGURE 3 is a fragmentary view showing the belt shifting actuator;

FIGURE 4 is a cross-sectional view taken on line IV—IV of FIGURE 3; and

FIGURE 5 is a cross-sectional view of the pump and a portion of the pulley driving system provided in accordance with the principles of the present invention.

As shown on the drawings:

Although the principles of the present invention may

2

be of general utility to any two-element drive system, the principles of the present invention find a particularly useful application when considered in the organization of laundry apparatus and specifically in combination washer-dryer.

In FIGURE 1 there is shown a combination washer-dryer indicated generally at 10 having a cabinet 11 with a control console 12 on which is provided a selector means 13 for presetting a sequential control means shown diagrammatically at 14. The presettable sequential control means 14 may be adjusted by the machine operator and thereafter operates the washer-dryer through a programmed series of soaking, washing, rinsing, extracting and drying steps so that a batch of materials to be treated may be placed in the machine 10 in soiled condition and automatically subjected to a complete washing and drying cycle in the same machine for removal from the machine in a completely laundered condition.

In the machine of the present invention, there is provided a tub shown generally at 16 in which a drum is rotated on a horizontal axis and having a drive shaft 17 to which is connected the hub 18 of a pulley wheel 19. It will be understood that a batch of materials may be introduced into the drum and subjected to treatment in the treatment zone prescribed by the tub 16.

In order to conduct washing operations in the treatment zone 16, means forming a hydraulic circuit are provided including the treatment zone 16 and further including appropriate conduits 20 and valving such as shown at 21. At one point in the hydraulic circuit, a pump is provided which pump is shown at 22 and is connected to the hydraulic circuit as at 23, thereby to drive a stream of liquid through the hydraulic circuit to recirculate the fluid through treatment zone 16. It will be further understood that the pump 22 may be employed to withdraw liquid from the treatment zone 16 and may also be used to direct liquid from the treatment zone 16 into an available drain or into a storage reservoir in order to save laundry liquid for a subsequent washing operation if it is so desired.

In order to provide adequate drying conditions within the treatment zone 16, means forming an air circuit are provided and at one point in the air circuit there is provided an air translating means taking the form of a blower 24 having a drive shaft 26 connected to a pulley wheel 27. The blower 24 may conveniently take the form of an air translating means of the centrifugal type having a center inlet receiving moist air from the treatment zone 16 and discharging the same into lint separator means 28. A heater box is shown diagrammatically at 29 for the purpose of adding thermal energy to the stream of air directed into the treatment zone, thereby enhancing the ability of the stream of air to pick up moisture.

The pump 22 is shown in greater detail in FIGURE 5 and comprises a casing 30 having a pumping chamber 31 formed therein in which is rotated an impeller 32 carried on the end of a drive shaft 33. The pump has an inlet 34 and an outlet 36. The shaft 33 is journaled in spaced bearing means 37 and is lubricated by lubricant saturated wicks 38 contained within an enlarged reservoir 39.

Referring to the right-hand of the pump assembly, as shown in the orientation of FIGURE 5, a bearing assembly is provided including an inner race ring 40 which is carried on the shaft 33 and an outer race ring 41 is carried on the inside diameter of a pulley wheel 42. A plurality of shiftable elements such as balls 43 are interposed between the inner and outer race rings 40 and 41, thereby to journal the pulley wheel 42 for rotation relative to the shaft 33.

Axially outwardly of the pulley wheel 42, there is provided a second pulley wheel 44 which is shouldered against

the inner race ring 40 as at 46 and which is clamped into co-rotatable assembly with the shaft 33 by means of a nut 47 threadedly engaged with a threaded end portion 48 formed on the end of the shaft 33. Thus, while the pulley wheel 42 is rotatable relative to the shaft 33, the pulley wheel 44 is co-rotatable with the shaft 33.

In order to drive the drum via the pulley wheel 19, the blower 24 via the pulley wheel 27 and the pump 22 via the pulley wheel 44, a drive motor and speed changing mechanism is provided which is shown generally at 51. In a normal laundering cycle, the drum is selectively operated either at a tumbling speed for effecting a washing or a rinsing action and at a higher centrifuging speed for effecting an extracting operation. Thus, the motor and speed changer 51 is shown as provided with two separate shaft outputs 53 and 54, the shaft 53 being connected to a pulley wheel 55 and the shaft 54 being connected to a pulley wheel 56. A pulley belt 57 is entrained over the pulley wheel 56 and over the pulley wheel 19, thereby to rotatably drive the shaft 17 and the drum within the treatment zone 16 either at a tumbling speed or at centrifuging speed, or conceivably at other intermediate speeds as may be desired in the operation of the machine 10. A pulley belt 52 is entrained over the pulley wheel 55.

Referring now to FIGURE 1 in connection with FIGURE 5, it will be noted that the pulley belt 52 selectively engages either the pulley wheel 44 or the pulley wheel 42. When the belt 52 engages the pulley wheel 44, the shaft 33 is rotated and the pump 22 is operated.

When the belt 52 engages the pulley wheel 42, the pulley wheel 42 drives a pulley belt 60 which is trained over the pulley wheel 27, thereby to drive the blower 24. In this connection, note that the pulley wheel 52 is constructed with two peripheral grooves 61 and 62. The pulley wheel 44 is also provided with a peripheral groove 63. The grooves 62 and 63 are positioned directly adjacent one another and the groove 61 is located at a position of a slightly larger diameter, thereby providing a radial shoulder 64 so that the pulley belt 52 may be quickly and conveniently shifted between the groove 62 and the groove 63, thereby to selectively engage or disengage a corresponding pulley wheel.

A pulley shifting mechanism is provided which is more clearly illustrated in FIGURES 3 and 4.

As illustrated in FIGURE 4, a bracket 70 has as a part thereof a bushing 71 flanged as at 72 for retention by a fastening means 73. The bushing has a cut out providing a cam surface 74 which extends both radially and axially in a circumferential direction relative to a shaft 76 which extends through the bushing 71 and is supported for both axial and rotatable movement with respect thereto.

The shaft 76 has extending radially outwardly thereof a lever arm 77 which is firmly connected to the shaft 76. One end of the lever arm 77 is connected as at 78 to a coil spring 79, the other end of the spring 79 being connected as at 80a to a plunger 81 of a solenoid motor shown generally at 82.

At the other end of the shaft 76, there is provided a belt actuating member 80 having a U-shaped groove 81 adapted to receive the pulley belt 52. A coil spring 83 extends between the actuator 80 and the flange 72 of the bushing 71. Thus, the coil spring 79 together with the coil spring 83 operates as a continuous biasing means for keeping the lever arm 77 in engagement with the cam surface 74 and the shaft 76 will thus be normally biased to a first position corresponding to a first position of the belt 52 on one of the pulley wheels 42 and 44.

When the solenoid motor 82 is energized, the lever arm 77 will be moved against the cam surface 74 thereby moving the shaft 76 axially inwardly against the bias of the spring 83 and the pulley belt 52 will be shifted from the dotted line position to the full line position, as shown in FIGURE 4.

Since the solenoid motor 82 is electrical, it can be

readily integrated into the automatic sequential control means associated with the machine and thus, the solenoid motor 82 may be directly controlled by the presettable sequential controller 14 so that the belt 52 will be shifted to inactivate the blower whenever the machine is operating in a washing cycle and to inactivate the pumping means whenever the machine is operating in a drying cycle.

By virtue of the provisions made by this invention, it will be appreciated the blower will not be operated during the washing cycle thereby preventing the blower housing from becoming wet and preventing lint build up in the air circuit portions of the machine. Further, water vapor in the treatment zone will not be extracted by the inactivated blower. It will also be noted that the selective operation of the pump and blower will materially reduce the total operating time of each respective portion of the machine, thereby saving wear and tear of the pump and blower components and extending the total machine life and effectiveness. A driving motor of lesser total power capacity may also be effectively employed without loss of functional advantage and with a corresponding reduction in expense.

Although minor modifications might be suggested by those versed in the art, it should be understood that I wish to embody within the scope of the patent warranted hereon all such modifications as reasonably and properly come within the scope of my contribution to the art.

The embodiments of the invention in which an exclusive property or privilege is claimed are defined as follows:

1. A combination washer-dryer comprising means forming a treatment zone in which materials are placed for successive washing and drying operations, means forming a hydraulic circuit including said treatment zone, pumping means in said hydraulic circuit for driving a stream of liquid through said hydraulic circuit and for removing the liquid from the circuit in connection with the washing operations, means forming a pneumatic circuit including said treatment zone, blower means in said pneumatic circuit for driving a stream of air through said treatment zone in connection with said drying operations, a common drive motor for said pumping means and said blower means, and a clutching apparatus comprising a pulley wheel for each of said pumping and blower means, a pulley belt having a driven connection with said drive motor, and a belt-shifting means for inactivating said pumping means during drying operations and for inactivating said blower means during washing operations by shifting said pulley belt between said pulley wheels.
2. A combination washer-dryer as defined in claim 1, said belt-shifting means comprising an electrically operated control motor, and a sequential control means for automatically operating said machine through a series of washing and drying periods and being in control of said control motor to automatically activate and inactivate said pumping and blower means at corresponding portions of the program.
3. A combination washer-dryer as defined in claim 1, said belt-shifting means comprising a solenoid motor having a coil and a plunger, a bracket having a shaft axially and rotatably shiftable therein, said bracket having a cam surface extending circumferentially around said shaft in radial and axial direction,

a lever arm connected to said shaft and to said plunger and engaging said cam surface, biasing means urging said shaft and said lever arm to a first position relative to said cam surface and corresponding to a first position of said pulley belt on one of said pulley wheels,

said plunger upon actuation of said solenoid moving said lever arm to axially shift said shaft against said biasing means, and a belt-engaging actuator carried on the end of said shaft to move said pulley belt from one pulley wheel to the other.

4. A combination washer-dryer as defined in claim 3, and a sequential control means for automatically operating said machine through a series of washing and drying periods and being in control of said control motor to automatically activate and inactivate said pumping and blower means at corresponding portions of the program.

5. A combination washer-dryer comprising means forming a treatment zone in which materials are placed for successive washing and drying operations, a rotatable drum in said treatment zone, hydraulic circuit means including a pump operable during the washing operation of said washer-dryer, 25 pneumatic circuit means including a blower for operation during the drying operations of said washer-dryer,

and a common drive motor for said drum, said pump and said blower, said drive motor having a speed-changing means for driving said drum at tumbling speed and at centrifuging speed,

and a clutching apparatus operatively connecting said drive motor with said pump and said blower to activate said blower only during drying operations and to activate said pump only during washing operations,

said clutching apparatus comprising a pulley wheel for each of said pump and said blower,

a pulley belt having a driven connection with said drive motor,

and belt shifting means for inactivating said pump during drying operations and for inactivating said blower during washing operations by shifting said pulley belt between said pulley wheels.

6. A combination washer-dryer as defined in claim 5, said belt-shifting means comprising an electrically operated control motor,

and a sequential control means for automatically operating said machine through a series of washing and drying periods and being in control of said control motor to automatically activate and inactivate said pump and said blower at corresponding portions of the program.

7. A belt-shifting means for a pulley system comprising a solenoid motor having a coil and a plunger, a bracket having a shaft axially and rotatably shiftable therein,

said bracket having a cam surface extending circumferentially around said shaft in radial and axial direction,

a lever arm connected to said shaft into said plunger and engaging said cam surface, 60 biasing means urging said shaft and said lever arm to a first position relative to said cam surface and corresponding to a first position of a pulley belt to be acted upon by said belt-shifting means,

said plunger upon actuation of said solenoid moving said lever arm to axially shift said shaft against said biasing means, and a belt engaging actuator carried on the end of said shaft and engageable with the pulley belt to physically transpose the position of the pulley belt for belt-shifting purposes.

8. In combination with a laundering apparatus having at least two pulley driven components, the improvement of a clutching apparatus comprising a pulley wheel for each of the pulley driven components, a pulley belt having a driven connection with a source of motive power, and belt-shifting means for selectively inactivating said pulley wheels by shifting said pulley belt between said pulley wheels.

9. In combination with a laundering apparatus as defined in claim 8, said belt-shifting means comprising an electrically operated control motor, and a sequential control means for automatically operating said laundry apparatus through a series of separate periods of a program cycle and being in control of said control motor to automatically activate and inactivate corresponding components driven by the pulley at corresponding portions of the programmed cycle.

10. In combination with a laundering apparatus as defined in claim 8, 30 said belt-shifting means comprising a solenoid motor having a coil and a plunger, a bracket having a shaft axially and rotatably shiftable therein,

said bracket having a cam surface extending circumferentially around said shaft in radial and axial direction, a lever arm connected to said shaft and to said plunger and engaging said cam surface, biasing means urging said shaft and said lever arm to a first position relative to said cam surface and corresponding to a first position of said pulley belt on one of said pulley wheels,

said plunger upon actuation of said solenoid moving said lever arm to axially shift said shaft against said biasing means, and a belt engaging actuator carried on the end of said shaft to move said pulley belt from one pulley wheel to the other,

11. In combination with a laundering apparatus as defined in claim 10, and a sequential control means for automatically operating said machine through a series of separate periods in a programmed cycle and being in control of said control motor to automatically activate and inactivate said pulley driven components at corresponding portions of the programmed cycle.
